UNITED STATES PATENT OFFICE.

JOSHUA ROY KINCKINER, OF POTTSSTOWN, PENNSYLVANIA.

WATER COOLER.

Application filed November 30, 1920. Serial No. 427,355.

To all whom it may concern:

Be it known that I, JOSHUA ROY KINCKINER, a citizen of the United States, residing in Pottstown, in the county of Montgomery and State of Pennsylvania, have invented certain new and useful Improvements in Water Coolers, of which the following is a specification.

This invention has as its principal object 10 the provision of means whereby the passengers in a railway car are provided with a supply of water which is filtered, cool and palatable.

Another object of this invention is in the 15 provision of means whereby a water tank may be attached to the roof of a railway car in such manner as to occupy no useful space and connect with the delivery system in the car.

20 These and other like objects are attained by the novel construction and combination of parts hereinafter described and shown in the accompanying drawings, forming a material part of this disclosure, and in 25 which:—

Figure 1 is a transverse sectional view of a part of a railway car, showing the cooler as applied in accordance with the invention.

Figure 2 is a longitudinal sectional view 30 of the tank taken on line 2—2 of Fig. 1.

Figure 3 is a sectional view of the feed pipe leading from the tank to the service faucet, as enclosed in a vacuum tube.

Referring to the drawings in detail, the 35 numeral 10 designates a conventional type of railway passenger car having a floor 11, a double roof 12 and side walls 14.

Attached upon the lower side roof 15 of the car is a platform 16 having fastened to 40 it semi-elliptical springs 17 arranged in pairs which support a flat bottomed tank 18 having ends 20, secured to upwardly extending plates 21 fixed to the platform 16.

The upper portion 22 of the tank is semi-45 cylindrical and forms a vacuum chamber 23, a suction pipe 24 leading therefrom to the air pumps of the locomotive.

Disposed concentrically within the outer tank 22 is an inner water storage tank 25 having a removable cover 27 which is protected by the cap 28 on the outer tank 22, both covers being removable for the purpose of refilling the water tank 25.

50 Leading from the water tank 25 and passing 55 through the suction chamber 23 and outer tank 22 at the bottom, is a pipe 29 which

passes through the platform 16 and the roof 15, where it is bent, as at 30 to provide against damage by shocks, jars and vibration, it being controlled by a valve 31 and then enters a vertical tank 32 containing filtering material.

The filter tank 32 has hooks 33 secured to the rear at the top and bottom thereof adapted to engage with openings in the brackets 35, which are secured to the side wall 14 of the car.

Below the filtering tank 32 is a cooler 37 which is connected by a pipe having a union 38.

Around the cooler ice is tightly packed which can be supplied by opening a door 40 secured to a cabinet 41 surrounding the filtering tank 31 and the cooler 37 which rests upon a shelf 43 secured upon angles 44 extending from the side walls of the car and cabinet, the latter being recessed to contain a faucet 45 extending from the cooler.

In the modification shown in Fig. 3 the 50 pipe 29 is shown to be secured centrally of plugs 50 at its ends and encased in a tube 51 forming a vacuum chamber 52 with which is connected a cock 53 controlling a pipe 54, which, like the pipe 24, communicates with the pumps or vacuum system of 55 the car.

In operation, the caps of the supply tank are removed and the tank 25 filled with potable water from any convenient source, as by a flexible hose, the valve 31 being 60 closed. Upon opening the valve the water will pass through the pipe 29 to the filter 30 and thence into the tank 37 surrounded by ice and is withdrawn as desired.

Connections having been made from the 65 pipes 24 and 54 the water is maintained at an equable temperature free from becoming overheated or from freezing due to the vacuum surrounding the supply tank and outlet pipe.

From the foregoing it will be seen that 70 means are provided for supplying passengers at all times with a supply of cool and pure drinking water and that the supply means occupy no useful space within the 75 car.

Having thus described my invention, what I claim as new and desire to secure by Letters Patent, is:

1. In a railway car drinking supply system, an ice chamber, a service tank therein, 80 a supply tank on the roof of the car, an

auxiliary tank surrounding and separated from said supply tank, means whereby air may be exhausted from the space between said tanks, the means being supplied from 5 a distant source, and flexible tubular connections between said supply and service tanks.

2. In a railway car drinking supply system, an ice chamber, a service tank 10 therein, a supply tank, an outer tank spaced concentrically therefrom, resilient supports for said tanks resting on the side roof of the car and resilient tubular connections from said supply tank to said service tank.

3. A railway car fountain comprising an ice closet having a drain, a cooler tank in 15 said closet, controllable means for withdrawing the contents of said cooler, a filter 20 tank over said cooler connected therewith, a supply tank on the side roof of the car, a second tank circumjacent thereto and having a space therebetween, the mentioned space 25 being exhausted of air and normally operating to prevent freezing the water in said supply tank, rigid connections between said tanks, resilient elements intervening between the roof and the outer of said tanks and means for filling said supply tank.

30 4. In a railway car water supplying de-

vice, a supply tank disposed longitudinally upon the roof of the car, a casing therearound by which said tank is supported, said casing forming a vacuum chamber, a platform on the roof below said casing, 35 spring elements interposed between said casing and said platform, a discharge pipe from said tank, a vacuum chamber through which said pipe passes, said pipe being bent to provide resilience, a filter into which said pipe leads, and a cooler communicating with said filter.

5. In a railway car drinking supply system, a refrigerating means comprising a cabinet for holding ice, a water cooling 40 tank surrounded by said ice, a filter in said cabinet disposed above the ice, a water supply tank secured to the exterior of said car, an auxiliary casing surrounding and supporting said supply tank, means whereby 45 the temperature of the water in the supply tank will be maintained above the freezing point by exhausting the air from between said supply tank and said auxiliary tank, and a yieldable tubular connection communicating from said supply tank to said filter.

In testimony whereof I have signed my name to this application.

J. ROY KINCKINER.
